DESIGN FOR A VALVE KEY FOR MUSICAL INSTRUMENTS

Morton S. Brockman, Cleveland, Ohio, assignor to Grossman Music Co., Cleveland, Ohio

Application January 6, 1945, Serial No. 117,311

Term of patent 14 years

(Cl. D56—1)

To all whom it may concern:

Be it known that I, Morton S. Brockman, a citizen of the United States, residing in the city of Cleveland, county of Cuyahoga, and State of Ohio, have invented a new, original, and ornamental Design for a Valve Key for Musical Instruments, of which the following is a specification, reference being had to the accompanying drawing, forming a part thereof.

Figure 1 is a side elevational view of a valve key for musical instruments showing my new design;

Figure 2 is a top plan view;

Figure 3 is a bottom view;

Figure 4 is a left side elevational view;

Figure 5 is a right side elevational view;

Figure 6 is a vertical cross sectional view of the key, taken along the line and in the direction of the arrows 6—6 of Figure 3; and

Figure 7 is a vertical cross sectional view of the key, taken along the line and in the direction of the arrows 7—7 of Figure 3.

The dominant features of my design reside in the portions shown by means of full lines in the drawing.

I claim:

The ornamental design for a valve key for musical instruments, substantially as shown and described.

MORTON S. BROCKMAN.
